UNITED STATES PATENT OFFICE

158,768

CABINET FOR AN ELECTRONIC CALCULATOR

George H. Kress, Vestal, N. Y., assignor to International Business Machines Corporation, New York, N. Y., a corporation of New York

Application May 7, 1949, Serial No. 2,524

Term of patent 14 years

(Cl. D64—11)

To all whom it may concern:

Be it known that I, George H. Kress, a citizen of the United States, residing at Vestal, in the county of Broome and State of New York, have invented a new, original, and ornamental Design for a Cabinet for an Electronic Calculator, of which the following is a specification, reference being had to the accompanying drawing, forming part thereof.

Fig. 1 is a perspective view of a cabinet for an electronic calculator embodying my design.

Fig. 2 is a right end view of the same.

Fig. 3 is a plan view of the same.

Fig. 4 is a front elevation of the same.

The back and the left end of the cabinet are plain.

I claim:

The ornamental design for a cabinet for an electronic calculator, as shown and described.

GEORGE H. KRESS.
